(57) **CLAIM**

The ornamental design for a carrying case or cover for a seat cushion, as shown and described.

DESCRIPTION

FIG. 1 is a front perspective view of a carrying case or cover for a seat cushion;

FIG. 2 is a front elevational view of the carrying case or cover for a seat cushion of FIG. 1;

FIG. 3 is a rear elevational view of the carrying case or cover for a seat cushion of FIG. 1;

FIG. 4 is a right-side elevational view of the carrying case or cover for a seat cushion of FIG. 1;

FIG. 5 is a left-side elevational view of the carrying case or cover for a seat cushion of FIG. 1;

FIG. 6 is a top plan view of the carrying case or cover for a seat cushion of FIG. 1;

FIG. 7 is a bottom plan view of the carrying case or cover for a seat cushion of FIG. 1;

FIG. 8 is a front perspective view of the carrying case or cover for a seat cushion of FIG. 1 shown in a first folded configuration; and,

FIG. 9 is a front perspective view of the carrying case or cover for a seat cushion of FIG. 1 shown in a second inverted folded configuration.

The broken lines are included for the purpose of illustrating portions of the carrying case or cover for a seat cushion that form no part of the claimed design.

1 Claim, 7 Drawing Sheets
